A. G. STEPHENS

DISPLAY CASE WARMER

Filed July 5, 1921

Patented July 31, 1923.

1,463,179

UNITED STATES PATENT OFFICE.

ALBERT G. STEPHENS, OF INDIANAPOLIS, INDIANA.

DISPLAY-CASE WARMER.

Application filed July 5, 1921. Serial No. 482,312.

To all whom it may concern:

Be it known that I, ALBERT G. STEPHENS, a citizen of the United States, residing at Indianapolis, in the county of Marion and 5 State of Indiana, have invented new and useful Improvements in Display-Case Warmers, of which the following is a specification.

This invention relates to the retail sale 10 of peanuts and like commodities which are more appetizing and salable hot than cold, and the object of the invention is to attractively display the nuts in a practically airtight glass container which will protect them 15 from moisture and other atmospheric conditions while exposing the quality of the stock to the customer at all times.

A further object is to remove the contents 20 always from the bottom so all of the stock will be uniformly taken out instead of portions being allowed to remain to become stale as would occur if removal was from the top.

Another and very important object of my 25 invention is to keep only that limited part of the contained product hot which is at the discharge outlet, and to avoid heating the remaining and by far the major portion which would become rancid and stale if 30 heated for many hours before being sold, particularly if subjected to alternate heat and cold, as heat during the business hours of the day and cold during the closed hours at night.

35 I accomplish the above principal objects, and other minor ones which will hereinafter appear, by the mechanism illustrated in the accompanying drawing, in which—

Fig. 1, is a front perspective view of my 40 invention. Fig. 2, is a longitudinal vertical section on the line 2—2 of Fig. 3, and Fig. 3 is a vertical cross section on the line 3—3 of Fig. 2.

Like characters of reference indicate like 45 parts in the several views of the drawing.

In the embodiment of my invention shown in the drawing a horizontal floor or base 4 forms the support for a rectangular box comprising a front 5 a back 6 and the ends 50 7 and 8. The upper edge of this box will preferably be widened by a frame 9. Resting upon the frame 9 is a rectangular glass superstructure comprising a front 10, back 11, ends 13, and a top 14, which is fastened to the frame 9 by means of metal angle-plates 15. The rectangular superstructure thus

formed is divided into the desired number of compartments, here shown as five, *a*, *b*, *c*, *d* and *e*, by means of glass partitions 16. This separation is made for the purpose of 60 providing independent receptacles for nuts of different kinds or differently prepared ones of the same kind. As shown in Fig. 1, compartment *a* is made a depository for filberts, compartment *b* for shelled and unsalted peanuts, compartment *c* for peanuts in the shell, compartment *d* for shelled salted peanuts and compartment *e* for shelled pecans.

Each of said compartments discharges 70 into a separate hopper 16 in the form of a truncated inverted pyramid, which will preferably be made out of sheet metal having a highly polished inner surface. Each hopper 16 discharges into an individual trough 75 comprising vertical and parallel side walls 18, and a combined front and bottom 19, which in effect is a continuation on a curve of the front of the hopper 16.

The back 6 of the rectangular box is provided with a discharge opening opposite each of the hopper-troughs, and the combined front and bottom 19 extends on a gradual curve from the front hopper-wall 16 to the bottom of the discharge opening in 80 side 6, where it is secured in any usual and suitable manner. The sides 18 of the troughs extend into and part way through their respective discharge openings in side 6, in the manner shown in Fig. 3. Each of said discharge openings is provided with a metal door 20 which is hinged at its bottom to the bottom of its opening, and to keep the nuts from falling out on each side of the door when the latter is opened, I provide the 85 metal side-plates 21 which are moved back and forth between the respective trough-walls 18 and adjacent sides of the openings in the member 6. These plates have suitable projections 22 to contact with the member 6 and limit the opening of door 20 to about the angle shown in Fig. 3, which is above a horizontal plane, to arrest the discharge of nuts when the door is opened.

As the consuming public prefers hot peanuts and cold filberts and pecans, I provide an electric heating unit 24, which is secured by metal straps 25 riveted to the undersides of the hopper bottoms 19, close to the discharge openings through the box-side 6. 105 This electrical heating unit extends under the troughs of receptacles *b*, *c*, and *d*, as

shown in Fig. 2, but does not extend under trough receptacles *a* and *e*; and it is insulated from the hoppers and troughs of receptacles *a* and *e* by asbestos partitions 26. 5 The bottom 4 is insulated by an asbestos lining 27. The electrical heating element 24 is in circuit with any suitable source of current (not shown), and attached to the end 8 of the box is a switch 29 of usual construction. 10 The shapes of the hoppers and their troughs leave ample room in the box in which they are assembled for the installation of a lamp 30, which is opposite a window 31 in the front 5 of the box, and on this window 15 I preferably display a legend calling attention to the hot nuts offered for sale.

The side 11 of the glass superstructure is in two horizontally divided parts to provide a door member 33 capable of being opened 20 for the renewal of the contents of the several compartments of the superstructure. This member 33 is secured by hinges 34 and a latch 35, and to add to the strength of the glass superstructure on this side, which is 25 subjected to considerable strain in opening and closing the door, I provide metal angle-plates 36' which are bolted to the adjacent glass members.

To keep the heat from the electrical heating 30 unit out of the nuts in the hopper and receptacle discharging into it, and also to further restrain the discharge from the hopper, I provide a plate-extension 36 inwardly of the hopper from the inner edge of its rear 35 wall 16.

The operation of my invention is as follows: The receptacles are filled with the desired kinds and quantities of nuts through the opening closed by door 33, and they will 40 move down by gravity filling the hoppers of each compartment and limited quantities will pass through the hoppers into the troughs below, where the flow will be checked by the curved bottoms 19, assisted by the 45 plate-extensions 36. The nuts will bank part way up the closed doors 20 but will not reach the top of the discharge openings of the side 6. The quantity of nuts immediately over the electrical heating element 24 50 will be heated and kept hot by said element, while the mass stored in the hoppers and receptacles above will be only slightly warmed, so as to keep them dry and crisp. When a door 20 is open to the position as 55 shown in Fig. 3, to serve a customer, the nuts will be removed with a hand-scoop in the usual manner, and only the hottest nuts

will be taken out; they will be immediately replaced by automatic discharge through the hopper. 60

Having thus fully described my invention what I claim as new and wish to secure by Letters Patent of the United States is—

1. In a display vending and warming-case, a glass receptacle, a hopper having a discharge opening through which the receptacle discharges through said hopper, a plate extending inwardly of the hopper from the inner rear edge of the hopper, a curved side and bottom against which the hopper discharges and which in part define a trough, said trough having a discharge at one side of the hopper discharge, a hinged closure for the trough discharge, and a heating element under said trough discharge adjacent 75 said closure to warm the vended product. 70

2. In a display, vending, and warming-case, a box, a glass superstructure supported by the box, a hopper bottom for said superstructure in the form of an inverted truncated pyramid, a plate extending inwardly of the hopper from the inner rear edge of the hopper, members forming a trough into which the hopper discharges said members comprising a side and bottom which slope 85 gradually from the lower edge of the front of the hopper to a discharge opening in the back of the box, a removable closure for the discharge in the back of the box and an electrical heating element under the trough near 90 said closure. 80

3. In a device for the purposes specified, a box having a sight opening in its front through which a legend stating the heated condition of the box contents may be viewed, 95 said box having a discharge opening through its back, a receptacle superimposed upon the box having a bottom in the form of an inverted truncated pyramid, a restricted discharge from the bottom of the receptacle 100 through the opening in the back of the box, said bottom sloping toward the opening to mass the contents near the opening, a door hinged at its lower edge forming a closure 105 to the discharge opening in the box, an electrical heating element under said massed contents and an electric light opposite the sight opening and located within the box to attract attention to a legend when exposed 110 through the opening. 105

Signed at Indianapolis, Indiana, this 1st day of July, 1921.

ALBERT G. STEPHENS.
